UNITED STATES PATENT OFFICE.

LAWRENCE YERGER, OF JACKSON, MISSISSIPPI, ASSIGNOR TO JENNIE B. YERGER, OF JACKSON, MISSISSIPPI.

TYPE-WRITER COVER.

1,247,057.

Specification of Letters Patent. Patented Nov. 20, 1917.

Application filed September 9, 1916. Serial No. 119,181.

To all whom it may concern:

Be it known that I, LAWRENCE YERGER, a citizen of the United States, residing at Jackson, in the county of Hinds, State of 5 Mississippi, have invented a new and useful Type-Writer Cover; and I do hereby declare the following to be a full, clear, and exact description of the invention, such as will enable others skilled in the art to which 10 it appertains to make and use the same.

The present invention relates to certain new and useful improvements in typewriter covers, and has for its object to provide a device of this character which embodies 15 novel features of construction whereby the typewriter is automatically moved into operative position when the cover is opened, and the cover automatically closed when the typewriter is released and moved into inoperative position, thereby making it very easy 20 to take proper care of a typewriter and keep it covered when not in use.

Further objects of the invention are to provide a typewriter cover or hood which is 25 comparatively simple and inexpensive in its construction, which can be either built into a table or desk or constructed as a separate unit, which admits of the typewriter being quickly moved back and forth from operative to inoperative position, and vice versa, 30 and which can be adjusted to operate satisfactorily with any standard make of typewriter.

With these and other objects in view, the 35 invention consists in certain novel combinations and arrangements of the parts as will more fully appear as the description proceeds, the novel features thereof being pointed out in the appended claims.

For a full understanding of the invention, 40 reference is to be had to the following description and accompanying drawing, in which:—

Figure 1 is a longitudinal sectional view 45 through a typewriter cabinet constructed in accordance with the invention, the doors being shown in a closed position with the typewriter carrying slide drawn rearwardly and housed within the hood.

Fig. 2 is a horizontal sectional view on 50 the line 2—2 of Fig. 1, showing the doors as swung outwardly and rearwardly into an open position and the typewriter carrying slide as moved forwardly into operative 55 position.

Corresponding and like parts are referred to in the following description and indicated in all the views of the drawings by the same reference characters.

Referring to the drawings, which illustrate one embodiment of the invention, the numeral 1 designates a base board which has a length or depth somewhat greater than that of a standard typewriter, the rear end of the base board being provided with 60 a hood 2 which is open at the front, and which is of a sufficient height to receive a typewriter. In the present instance this hood 2 extends over substantially the rear half of the base board 1. A slide 3 upon 65 which the typewriter is designed to be mounted is superposed upon the base board 1. The rear end of the slide is provided with the laterally projecting wings 3^a which may engage the side walls of the hood 2 to 70 assist in directing the slide in its back and forth movements, while the forward end of the slide is provided at substantially the middle portion thereof with a downwardly 75 projecting ear 4 which is received within a longitudinal slot 5 formed in the top of the 80 base board 1. The bottom of the slide 3 is also provided with rollers 6 which reduce the friction and enable the slide to move freely back and forth upon the base board 85 as the device is operated.

A tension spring 7 is arranged within the groove 5 of the base board, the forward end of the said spring being connected to the ear 4 of the slide, while the rear end 90 thereof is connected to a threaded stem 8 which extends rearwardly through the back of the hood 2 and has an adjusting screw 9 applied thereto. With this construction it will be obvious that by manipulating the adjusting screw the tension of the spring 7 can be increased or decreased, depending upon the weight of the typewriter which is mounted upon the slide. This spring normally tends to draw the slide back into 100 inoperative position at the rear end of the base board 1, and when the slide is pulled forwardly into operative position, an opening in a latch plate 10 at the forward end of the slide engages the nose of a 105 spring latch 11 upon the base board, thereby holding the slide against the action of the spring. However, as soon as the spring catch 11 is disengaged from the latch plate 10 the slide 3, together with the typewriter 110

mounted thereon, is drawn rearwardly into inoperative position by the action of the spring 7. Suitable sockets 12 are provided upon the slide 3 for engaging the feet of the typewriter.

The open front of the hood 2 is arranged to be closed by means of a pair of doors 13 which are constructed to overhang the forward end or keyboard of the typewriter, and provide, in effect, a forward extension of the hood 2 when in a closed position. For this purpose the doors are formed with downwardly and forwardly inclined tops 13^a and fronts 13^b which project laterally from sides 13^c, said sides being hingedly connected at 14 to the sides of the hood 2. Knobs or finger pieces 15 are provided at the front of the doors 13 for manipulating the same, and the doors are adapted to be swung outwardly and rearwardly into inoperative position against the sides of the hood 2 when the slide 3 is drawn forward to bring the typewriter into operative position. The edges of the doors 13^a and the forward edges of the hood 2 are correspondingly rabbeted or beveled, as indicated at 16, in order to provide tight joints and eliminate open crevices when the doors are closed.

Means are provided for automatically moving the slide forward to bring the typewriter into operative position when the doors 13 are opened. For this purpose the side 13^c of each door is provided upon the interior thereof with a rearwardly extending arm 17 which is slightly offset inwardly therefrom so as to fit against the inner faces of the side walls of the hood 2 when the covers are closed. These arms 17 are provided at the forward ends with flanges 17^a which are secured to the doors 13, and at the rear ends with wings 17^b which are pivotally connected to link members 18, the rear ends of the said link members being pivotally connected at 19 to the respective laterally extending wings 3^a at the rear end of the slide 3. With this construction, it will be obvious that when the doors 13 are opened the slide 3 will be drawn forward and the latch plate 10 at the forward end thereof brought into engagement with the spring catch 11, thereby locking the typewriter in operative position. When the operator is through using the typewriter, it is merely necessary for him to release the spring catch 11, whereupon the tension spring 7 will draw the slide 3 rearwardly into the hood 2, simultaneously closing the doors 13. The typewriter is then tightly housed so as to be protected from dust and dampness and there is little occasion for a careless operator to leave the machine uncovered over night or when not in use.

The inner sides of the door 13 are provided toward the top thereof with transverse straps 20, and toward the bottom there-

of with pockets 21, said straps and pockets being adapted to coöperate with each other to receive envelops or the like, and to hold them in such a position that they are readily accessible when the cover or hood is opened up and the typewriter is in operative position. A pencil engaging clip 22 may also be applied to the inner faces of the sides 13^c of the doors. For the purpose of receiving letter heads or the like a shelf 23 may be provided immediately under the top of the hood 2, and the forward end of the top of the hood 2 may be formed with a transversely extending hinged strip 24 which can be swung upwardly to admit of the letter heads or paper upon the shelf 20 being easily grasped by the hand of the operator. Everything is thus within easy reach of the operator, so that much time will be saved in getting paper and envelops, and everything is arranged to be tightly housed when the typewriter is not in use.

Having thus described the invention, what I claim as new and desire to secure by Letters Patent, is:—

1. A typewriter cabinet including a base, a hood extending over the rear end of the base and having an open front, a typewriter carrying slide mounted upon the base and movable back and forth thereon, the length of the hood being less than that of the typewriter carrying slide, a spring normally tending to move the slide rearwardly into the hood, a pair of corresponding outwardly and rearwardly swinging doors hingedly connected to the opposite sides of the hood and adapted to close the open front thereof, said doors being bulged forwardly and constructed for coöperation with each other to provide a forward hood extension to inclose the forward end of the typewriter carrying slide, an operative connection between the doors and the slide for moving the slide forward when the doors are opened and closing the doors when the slide is permitted to move rearwardly, and a detent for locking the slide in a forward position.

2. A typewriter cabinet including a base having a forwardly and rearwardly extending groove therein, a hood extending over the rear end of the base and having an open front, a typewriter carrying slide mounted upon the base and movable back and forth thereon, the length of the hood being less than the length of the typewriter carrying slide, an ear projecting from the slide into the groove of the base, a tension spring arranged within the groove and connected to the ear, said spring normally tending to draw the slide rearwardly, a pair of corresponding upwardly and rearwardly swinging doors hingedly connected to the opposite sides of the hood and adapted to close the open front thereof, said doors being bulged forwardly for coöperation with each other

- to provide a hood extension to inclose the forward end of the typewriter carrying slide, an operative connection between the doors and the slide for moving the slide forwardly when the doors are opened, and a 5 detent for locking the slide in a forward position.
3. A typewriter cabinet including a base, a hood extending over the rear end of the 10 base and having an open front, a typewriter carrying slide mounted upon the base and movable back and forth thereon, the length of the hood being less than the length of the slide, a spring connected to the slide and 15 normally tending to move it rearwardly, a pair of corresponding outwardly and rearwardly swinging doors hingedly connected to the opposite sides of the hood and adapted to close the open front thereof, said doors 20 being bulged forwardly for coöperation with each other to provide a hood extension to inclose the forward end of the typewriter carrying slide, rearwardly extending arms rigidly connected to the sides of the doors 25 and extending into the hood when the doors are closed, link connections between the said arms and the slide for automatically moving the slide forwardly and rearwardly as the doors are opened and closed, and a detent 30 for locking the slide in a forward position.
4. A typewriter cabinet including a base having a forwardly and rearwardly extending groove therein, a hood extending over the rear end of the base and having an open 35 front, a typewriter carrying slide mounted upon the base and movable back and forth thereon, the length of the hood being less than the length of the typewriter carrying slide, an ear projecting from the slide into 40 the groove of the base, a tension spring arranged within the said groove and connected to the ear so as to normally tend to draw the slide rearwardly, a pair of opposed outwardly and rearwardly swinging doors 45 hingedly connected to the opposite side of the hood and adapted to close the open front

thereof, said doors being bulged forwardly so as to coöperate with each other to form a hood extension to inclose the forward end of the typewriter carrying slide, rearwardly 50 extending arms rigidly applied to the sides of the doors and arranged to project into the hood when the doors are closed, link connections between the arms and the slide for automatically moving the slide forwardly 55 and rearwardly as the doors are opened and closed, and a detent for locking the slide in a forward position.

5. A typewriter cabinet, including a base having a forwardly and rearwardly extending groove therein, a hood extending over the rear end of the base and having an open front, a typewriter carrying slide mounted upon the base and movable back and forth thereon, said slide being provided with laterally 60 extending wings which slidably engage the sides of the hood, and also with a downwardly projecting ear which is received within the groove of the base, the said wings and ear serving to direct the 65 slide in its movements, a spring arranged within the groove of the base and connected to the ear of the slide for normally moving the slide rearwardly into inoperative position, a pair of outwardly and rearwardly 70 swinging doors hingedly connected to the sides of the hood and adapted to close the open front thereof, rearwardly extending arms applied to the doors, link connections between the said arms and the laterally extending wings of the slide for automatically 75 moving the slide forwardly and rearwardly as the doors are opened and closed, and a spring detent for releasably holding the slide in a forward position. 80

In testimony whereof I have signed my name to this specification in the presence of two subscribing witnesses.
